UNITED STATES PATENT OFFICE.

WILLIAM PETER SIMPSON, OF HOBSONVILLE, AUCKLAND, NEW ZEALAND.

SAFETY LIFTING HOOK.

1,409,068.

Specification of Letters Patent.

Patented Mar. 7, 1922.

Application filed November 20, 1920. Serial No. 425,367.

To all whom it may concern:

Be it known that, WILLIAM PETER SIMPSON, citizen of New Zealand, residing at Hobsonville, Auckland, has invented certain 5 new and useful Improvements in Safety Lifting Hooks, of which the following is a specification.

This invention relates to hooks used on 10 cranes, derricks and the like for lifting cargo and other loads, and provides an improved form of safety hook for the aforesaid purpose.

According to the invention the hook is formed with a flattened upper portion on 15 either side of which the sides of a forked keeper pass, said forked keeper being pivoted to the flattened portion near the edge thereof located over or nearest the hook point.

20 The flattened portion of the hook contains an arcuate slot concentric with the pivot of the keeper, and at the lower end of said slot, in the side edge thereof furthest from the pivot, a slight recess is provided.

25 Both sides of the forked keeper contain a slightly elongated hole through both of which and the slot in the flattened portion of the hook, the link of a lifting chain or a rope is passed.

30 The point of the hook has a raised central portion thereon on which the grooved lower end of the keeper locks, so that side play of the latter is prevented.

The invention will be further described 35 with reference to the accompanying drawing, in which:—

Figure 1 is an elevation of the hook closed, Figure 2 shows same open,

40 Figure 3 is an elevation of the hook with the keeper removed, and

Figure 4 is an edge view of the latter.

In the drawing 1 is the hook and 2 the flattened upper portion of same.

45 The sides of the forked keeper 3 pass one on each side of the flattened upper portion 2 and are pivoted thereto by a pin 4 which is located near the edge of said portion 2 over the hook point.

The flattened upper portion of the hook 50 1 contains an arcuate slot 5 concentric with the keeper pivot pin 4, while opposite and slightly elongated holes 6 are formed in the sides of the forked keeper 3.

The portion 2 has a slight recess 9 merging into the lower end of the slot 5 and ar-

ranged at the side edge of the slot which is furthest from the pivot pin 4.

The hook point is formed with a raised central portion 7 thereon, the latter being located in the same vertical plane as the flattened portion 2 of the hook 1, while the lower end of the keeper 3 is grooved as at 8 to pass on said raised portion 7 and prevent side play of the keeper.

The link 10 of a lifting chain or a rope 65 is passed through the holes 6 in the forked keeper and also through the slot 5 in the flattened portion 2.

When there is no load on the hook 1, the lower end of the keeper 3 can be raised off 70 the hook point to allow the bight of a rope or a sling to be placed on the hook. The raising of the lower end of the keeper 3 levered the hook 1 upwards until the link 10 or rope engages in the recess 9 in the 75 side of the slot 5, which retains the keeper raised and the hook open until such time as sufficient strain is put on the hook to cause the latter to move downwards on the link 10 or rope, the same movement forcing 80 the grooved lower end of the keeper 3 to close on the hook point.

The keeper 3 is kept closed by the weight of the suspended load until such time as the weight of the latter is taken off the hook, 85 whereupon the keeper 3 can be opened as before described.

What I do claim and desire to secure by Letters Patent of the United States is:—

1. A lifting hook having an upper portion 90 containing a slot the lower end of one side edge of which is recessed; a keeper adapted to close on the hook point, pivoted to the upper portion of said hook towards the edge of the latter over the hook point, and containing an elongated hole which registers with said slot, and a member passing through said hole and slot for holding the keeper in closed position.

2. A lifting hook having a flattened upper 100 portion containing a slot, the lower end of one side edge of which is recessed; a forked keeper adapted to close on the hook point, pivoted to said flattened portion towards the edge thereof over the hook point, and containing elongated holes which register with said slot, and a member passing through said holes and slot for holding the keeper in closed position.

3. A lifting hook having a flattened upper 110

portion containing an arcuate slot the lower end of one side edge of which is recessed; a forked keeper with a grooved lower end adapted to close on a central raised portion 5 on the hook point, pivoted to said flattened portion towards the edge of the latter over the hook point, and containing elongated holes which register with said slot, and a member passing through said holes and slot 10 for holding the keeper in closed position.

4. A lifting hook having a flattened upper portion, a pivot pin carried by said upper portion, said upper portion being provided with an arcuate slot concentric with said 15 pivot pin, said upper portion also having a recess arranged near the lower end of the slot and provided in the edge of said slot which is furthest away from said pivot pin, a forked keeper adapted to close on the hook 20 point and mounted on said pivot pin, said keeper being provided with slightly elongated holes registering with said slot, and a supporting member passing through the 25 holes and slot and adapted to engage said recess for holding the keeper in open position.

5. The combination with a hook having a flattened upper portion provided with a pivot hole and an arcuate slot concentric with said hole, of a fork-shaped keeper having tines engaging opposite faces of said upper portion and provided with a part engageable with the point of said hook, a pivot pin passing through said keeper and through said hole, the upper portion of said hook 30 being provided with a recess which merges into the lower end of said slot, said keeper being provided with aligned slightly elongated apertures which register with said slot, and a supporting member passing through 35 said slot, and adapted when occupying the upper end of said slot to hold said keeper in closed position, and when occupying said recess to hold said keeper in open position. 40 45

In testimony whereof I affix my signature in presence of two witnesses.

WILLIAM PETER SIMPSON.
